MICHIGAN, A CORPORATION OF MICHIGAN

BOILER CLEANER

Application filed February 18, 1924, Serial No. 693,609. Renewed September 17, 1931.

The invention relates to boiler cleaners and refers more particularly to that type having a blower element through which cleaning fluid such as steam or the like is discharged to clean the boiler tubes or other parts of the boiler. The invention has among its objects the provision of an improved boiler cleaner of the type mentioned.

With this as well as other objects in view, the invention further resides in the novel features of construction and combinations and arrangements of parts as more fully herein-after set forth.

In the drawings:

Figure 1 is a longitudinal cross section through a boiler cleaner embodying our invention;

Figure 2 is an end view thereof;

Figure 3 is a cross section on the line 3-3 of Figure 2;

Figures 4 and 5 are views partly in longitudinal section and partly in side elevation, showing modified constructions.

1 is the blower element adapted to discharge the cleaning fluid such as steam or the like upon the boiler tubes or other parts of the boiler. 2 is the boiler wall box mounted in an opening in the boiler setting 2^a through which the blower element extends and in which it is free to move. 3 is the head in which the cylindrical hollow body 4 is rotatably mounted. The blower element is rotated by suitable means such as the projections 5 upon the body 4 which loosely engage in the channels 6 in the adjacent end of the blower element. This body 4 has the valve seat 7 at its end adjacent to the end of the blower element and carries the axially movable valve 8 adapted to engage the seat 7 and control the passage of the cleaning fluid through the blower element. 9 are openings in the body placing its interior outwardly beyond the valve seat in communication with the inlet passageway 10 in the head 3 through which the cleaning fluid enters the body.

11 is the valve stem extending through the partition 12 within the body, which latter guides the valve stem. For conducting the steam or the like which leaks between the body 4 and the head from the openings 9 or

which leaks between the valve stem 11 and the guide partition 12, there is the passageway 13 in the guide partition which communicates with the annular groove 14 in the head 3. This annular groove communicates with the curved passageway 15 in the head which leads to the annular space between the blower element 1 and the sleeve 16, the inner end of this space communicating with the interior of the boiler. This annular space 16^a also communicates with the space between the head and body inwardly beyond the opening 9 in the body 4. Thus it is seen that with this construction, any cleaning fluid which leaks between the body 4 and the head 3 as well as between the valve stem 11 and the body 4 is conducted to the interior of the boiler.

For the purpose of opening and closing the valve we have, in the present instance, made use of a part of the mechanism for rotating the blower element. In detail, 17 is the sheave wheel of this mechanism around which may extend a flexible operating member such as a chain. 18 is a pinion rotated by the sheave wheel and meshing with the gear 19, which latter is fixed upon the body 4 as by set screws 19^a. This body 4 being operatively connected to the blower element 1 by the projections 5 loosely engaging in the slots 6, will rotate the latter and at the same time permit of mis-alignment between the head and the blower element. To permit swinging of the blower element its outer end is enlarged and provided with a spherical bearing face 20 for engaging a spherical bearing face 21 in the socket plate 22. Also, to permit movement of the blower element transverse to the axis of the body 4, the socket plate 22 is slidable transversely of the axis of the body.

The mechanism for moving the valve 8 to open and closed positions makes use of the gear 19. In detail, 23 is a plate at the outer end of the head 3 and secured to the valve stem 11 by suitable means such as the nut 24 at its outer side and the transverse pin 25 at its inner side. The plate is preferably provided on its inner side with a plurality of cams 26 concentric with its axis of rotation

- and the gear 19 is provided with a corresponding number of transverse pins 27 engageable with the cams 26, the latter being secured to plate 23 by studs 40'. The plate 5 is also provided with the stops 28 and 29 extending peripherally therebeyond and occupying different planes and engageable with the stationary stop 30 upon the bracket 31 which is secured to the head 3.
- 10 With the parts in the position indicated in Figures 1 and 2 and upon rotation of the sheave wheel 17 the blower element 1 is rotated by means of the pinion 18, gear 19, and body 4. Since the plate 23 cannot revolve owing to the stop 28 being in engagement with the stationary stop 30, each transverse pin 27 upon the gear 19 rides over the inclined surface 32 of its respective cam 26, thereby forcing the plate 23 outwardly.
- 15 20 When the pins have moved over the inclined surfaces 32 and come into engagement with the plain surfaces 33 of the cams, the plate 23 has been moved outwardly a sufficient distance to move the valve 8 to open position and 25 to disengage the stop 28 from the stationary stop 30 so that upon continued rotation of the gear 19 the plate 23 will be revolved. Rotation of the plate 23 continues until the stop 29 comes into contact with the stationary 30 stop 30 after which the transverse pins 27 ride over the next inclined surfaces 34 of their respective cams and then over the oppositely inclined surfaces 35. The inclined surfaces 34 assists in preventing pins 27 accidentally 35 riding off the cams 26. The plate 23 is thereupon allowed to resume its original position, at which time the stop 29 becomes disengaged from the stationary stop 30 and the valve 8 is in closed position. The valve is moved to 40 closed position by suitable means such as the coil spring 36 within the outer end of the body 4 and abutting a projecting ring 37^a formed on the inner end of the sleeve 37. This projecting ring 37^a fits snugly against 45 the body 4. Spring 36, at its opposite end abuts the projecting ring 4^a which is an integral part of plate 4^b. This plate, in turn, is fixed to body 4 and the hub of gear 19, in any suitable manner. The outer end of 50 sleeve 37 is engaged by the collar 38 sleeved upon the valve stem 11 and in engagement with the transverse pin 25.
- 55 For the purpose of varying the time of opening and closing the valve, the stops 28 and 29 are adjustably secured to the plate 23 by suitable means such as the bolts 39 and nuts 40 which are adapted to alternatively engage in peripherally-spaced openings 39' near the edge of the plate 23.
- 60 65 In the modified construction of boiler cleaner shown in Figure 4, labyrinth grooves 41 are provided in the periphery of the body 4 on opposite sides of the openings 9 and also outwardly beyond the passageway 13 in the body partition 12, these grooves assisting in

restricting the flow of the cleaning fluid between the body and head. Also, labyrinth grooves 42 are provided in the partition 12 and surrounding the valve stem 11, these grooves being preferably on opposite sides 70 of the partition passageway 13.

As shown in Figure 5, the passage of the cleaning fluid between the body 4 and head 3 is restricted by providing suitable packing 43 in the grooves 44. Also, suitable packing is 75 provided in the body 4 and surrounding the valve stem 11, this packing, as shown, being located in the groove 45 beyond the passageway 13 of the body partition. It is obvious that this packing, if used, may be formed of 80 soft material such as fibrous or the like material, or it may be formed of hard material such as metal and in the form of piston rings.

It will be noted that in each form of construction there is provided means for conducting to the interior of the boiler setting cleaning fluid which might escape either between the body 4 and the head 3 or between the valve stem 11 and the body partition 12. It will be apparent that while the body 4 is 85 shown as being flexibly connected to the blower element 1, this body is a swivel tube and constitutes in substance a portion of the blower element. Thus, in the claims, wherever the expression "contact surfaces between said 90 element and said head" is used there is meant the contact surfaces between a swivel tube such as the body 4, the blower head, whether this swivel tube be flexibly connected to the blower element as disclosed or whether this 95 swivel tube be formed as an integral part of the blower element.

What we claim as our invention is:

1. In a boiler cleaner, the combination with a head provided with a cleaning fluid supply pipe, of a rotary blower element and a body rotatably mounted in said head, an axially movable valve within said body provided with a stem, a guide for said stem, a passageway in said head communicating with the interior of the boiler, and a passageway in said guide communicating with said first-mentioned passageway, whereby cleaning fluid escaping past the contact surfaces between said stem and said guide may be conducted to said first-mentioned passageway and hence to the interior of the boiler.

2. In a boiler cleaner, the combination with a rotary blower element, and a valve for controlling the passage of cleaning fluid through said blower element, said valve being rotatable therewith, of means for rotating said blower element including a gear rotatable therewith, and cooperating means upon said gear and valve for axially moving said valve 115 to open and close the same.

3. In a boiler cleaner, the combination with a rotary blower element, and a valve for controlling the passage of cleaning fluid through said blower element, said valve be-

ing rotatable therewith, of means for rotating said blower element including a member rotatable therewith, and a cam member co-operating with said last-mentioned member 5 for axially moving said valve to actuate the same.

4. In a boiler cleaner, the combination with a head, of a rotary blower element mounted thereon, an axially movable valve for controlling the admission of cleaning fluid to said blower element, said valve having a stem in substantial axial alignment with said blower element, means for rotating said blower element including a gear, a transverse pin 10 upon said gear, a plate for moving said valve stem in one direction, and a cam upon said plate engageable with said transverse pin upon rotation of said gear.

5. In a boiler cleaner, the combination with 20 a head, of a rotary blower element mounted in said head, an axially movable valve adapted to control the passage of cleaning fluid through said blower element, a plate operatively connected to said valve, a cam upon 25 said plate, means for rotating said blower element including a gear, a transverse pin upon said gear adapted to engage said cam and thereby axially move said valve, and co-operating stops upon said plate and head controlling the engagement of said transverse 30 pin and cam.

6. In a boiler cleaner, the combination with a rotary blower element and a valve for controlling the passage of cleaning fluid through 35 said blower element, said valve being rotatable therewith, of means for rotating said blower element including a gear rotatable therewith, and means dependent upon rotation of said gear for moving said valve to 40 open and close the same.

7. In a boiler cleaner, the combination with a rotary blower element, and a valve for controlling the passage of cleaning fluid through 45 said blower element, said valve being rotatable therewith, of means for rotating said blower element including a member rotatable therewith and a cam member co-operating with said last mentioned member for moving said valve to actuate the same.

8. In a boiler cleaner, the combination with a head located exteriorly of the boiler setting and provided with a cleaning fluid supply pipe, of a blower element adapted to discharge cleaning fluid, said blower element being journalled in said head and adapted to 50 receive cleaning fluid therefrom, and means for conducting to the interior of the boiler setting, cleaning fluid escaping outwardly away from the boiler setting and past the contact surfaces between said element and said head.

9. In a boiler cleaner, the combination with a head located exteriorly of the boiler setting and provided with a cleaning fluid supply 55 pipe, of a blower element adapted to dis-

charge cleaning fluid, said blower element being journalled in said head and adapted to receive cleaning fluid therefrom, a valve mounted in said head and movable to control the supply of cleaning fluid to said element, an operating member for said valve, and means for conducting to the interior of the boiler setting, cleaning fluid escaping past the contact surfaces between said valve operating member and said head. 70

10. In a boiler cleaner, the combination with a head located exteriorly of the boiler setting and provided with a cleaning fluid supply pipe, of a blower element journalled in said head and adapted to receive cleaning fluid therefrom, a valve mounted in said head and movable to control the supply of cleaning fluid to said element, a stem for said valve, and a passageway for conducting to the interior of the boiler setting cleaning fluid escaping around the said valve stem. 80

11. In a boiler cleaner, the combination with a rotary blower element and a valve for controlling the flow of cleaning fluid to said element, of means for rotating said blower element including a member rotatable therewith, a plate-like member movable with said valve, a cam carried by the plate-like member and means carried by said rotatable member engageable with said cam for moving said plate-like member to actuate said valve. 90

12. In a boiler cleaner, the combination with a rotary blower element, of a head in which said element is journalled, said head being located exteriorly of the boiler setting and being adapted to a supply cleaning fluid to said blower element, a valve in said head to control the supply of cleaning fluid to said blower element, and a passage-way in said head adapted to conduct to a point inside the 100 boiler setting any cleaning fluid leakage escaping outwardly away from said boiler setting and past the moving parts of said head.

13. In a boiler cleaner, the combination with a rotary blower element, of a head in which said element is journalled, said head being located exteriorly of the boiler setting and being adapted to supply cleaning fluid to said blower element, a valve in said head to control the supply of cleaning fluid to said blower element and a passageway in said head forming a by-pass around the said valve, said passageway being adapted to conduct to a point inside the boiler setting any cleaning 110 fluid leakage escaping past the moving parts 115 of said head.

14. In a boiler cleaner, the combination with a head located exteriorly of the boiler setting, a wall box mounted in the boiler setting, and a blower element projecting through said wall box and journalled in said head for receiving cleaning fluid therefrom, of means providing a passageway for conducting to the said wall box cleaning fluid 125 130

escaping past the contact surfaces between said element and said head.

15. In a boiler cleaner, the combination with a head located exteriorly of the boiler setting, a wall box mounted in the boiler setting, and a blower element projecting through said wall box and journaled in said head for receiving cleaning fluid therefrom, of a passageway formed in said head for conducting to the said wall box cleaning fluid escaping past the moving parts of said head.

16. In a boiler cleaner, the combination with a head located exteriorly of the boiler setting, and a blower element projecting through said boiler setting and journaled in said head for receiving cleaning fluid therefrom, of a passageway formed in said head and extending from one side to the other side thereof for conducting to the interior of the boiler setting cleaning fluid escaping past the moving parts of said head.

17. In a boiler cleaner, the combination with a boiler setting, a rotary blower element projecting through said setting, a head in which said blower element is journaled, said head being located exteriorly of the boiler setting and being adapted to supply cleaning fluid to said blower element, and a passageway adjacent the blower element passing through said setting, of means in said head for conducting to the said passageway cleaning fluid escaping past the moving parts of said head.

18. In a boiler cleaner, the combination with a boiler setting, a rotary blower element projecting through said setting, a head in which said blower element is journaled, said head being located exteriorly of the boiler setting and being adapted to supply cleaning fluid to said blower element, a valve in said head for controlling the supply of cleaning fluid to said blower element, and a passageway passing through said boiler setting adjacent the said blower element, of a passageway in said head adjacent said valve for conducting to the first mentioned passageway cleaning fluid escaping past the moving parts of said head.

19. In a boiler cleaner, the combination with a boiler setting, a wall box projecting through the setting, a blower element projecting through the wall box and spaced from the inner periphery thereof to provide an annular passageway extending through said setting, and a head in which said element is journaled, said head being located exteriorly of the boiler setting and being adapted to supply cleaning fluid to said blower element, of means providing a passageway for conducting to the said annular passageway cleaning fluid escaping past the moving parts of said head.

20. In a boiler cleaner, the combination with a head located exteriorly of the boiler setting, and a blower element projecting

through said boiler setting and journaled in said head for receiving cleaning fluid therefrom, of means providing a passageway for conducting to the interior of the boiler setting cleaning fluid escaping past the moving parts of said head.

In testimony whereof we affix our signature.
